UNITED STATES PATENT OFFICE

WALTER HERBERT MAYHEW, OF TORONTO, OHIO

EXTRUDING DIE

Application filed December 19, 1929. Serial No. 415,269.

The invention relates to dies used in the manufacture of clay conduits, for the installation of electrical service lines, etc. Dies of this type have heretofore embodied a "hold-back" for preventing flow of the clay more rapidly along the side wall of the die, than at points nearer the center, and whenever adjustment of this "hold-back" has been necessary, it has been compulsory that portions of the die be disassembled, the adjustment being effected from the interior. It is one object of my invention to provide a new and improved construction, in which the "hold-back" may be readily adjusted inwardly or outwardly as may be required, by the manipulation of adjusting means accessible at the exterior of the die.

Dies of the type with which the present invention deals, include a plurality of spaced bells mounted on longitudinal stems which are secured to bridges spanning the die side wall, the bells being of non-circular shape corresponding to the shape of the various passes to be formed in the conduit. While rather effective provision has been made in the past for securing the stems to the bridges, said stems nevertheless often turn about their longitudinal axes, throwing the bells out of proper position and causing the production of faulty conduits. It is a further object of my invention to provide unique means to compensate for any such turning of the stems, by allowing a corresponding reverse turning of the bells upon the stems, the construction being such that this rectifying adjustment may be effected from the exterior of the die without disassembling any parts.

With the foregoing in view, the invention resides in the novel subject matter hereinafter described and claimed, description being accomplished by reference to the accompanying drawings.

Fig. 1 is a vertical transverse sectional view through an extruding die constructed in accordance with my invention.

Fig. 2 is a top plan view partly broken away.

Fig. 3 is a bottom plan view.

Fig. 4 is a perspective of one of the "hold-back" bars.

The drawings above briefly described illustrate the preferred form of construction, and while such construction will be herein specifically explained, it is to be understood that within the scope of the invention as claimed, variations may be made.

An extruding die is shown embodying a continuous side wall consisting of a main longitudinally tapered section 6 and a mouth ring 7 secured thereto, the two wall sections 6-7 being secured together in edge-to-edge relation. Preferably, the ring 7 is provided with outstanding lugs 8 contacting with the outer end of the main wall section 6, cap screws 9 being passed through these lugs and threaded into said wall section 6. The inner edge of the ring 7 is provided with a stepped formation as indicated at 10, providing a continuous internal groove 11. Slidably received in this groove, are hold-back bars 12 corresponding in number to the sides of the die wall. Adjusting screws 13 have their inner ends swiveled at 14 to the bars 12, said screws being threaded through openings 15 in the mouth ring 7. The outer ends of the screws 13 are accessible at the exterior of the die, and by turning these screws in the proper direction, the hold-back bars 12 may be adjusted inwardly or outwardly to insure the proper amount of projection from the die side wall, according to the character of the clay or the like being extruded, the pressure behind the clay, etc. As usual, the clay is contained in a hydraulic press, to the outlet of which the die is secured, the inner end of the main wall section 6 being provided with an outstanding flange 16 for attaching purposes.

A number of bridge bars 17 span the inner end of the die side wall and are secured to

90

the section 6 by cap screws or the like 18, the press-facing edges of said bars being preferably thinned as at 19, to offer little resistance to the clay forced outwardly from the press. The bridge bars 17 are formed with openings 20 in which integral studs 21 on the upper end of bell-carrying stems 22 are threaded, locking screws 23 being also threaded into said openings to lock the stems 22 against rotation insofar as possible. Regardless of the stem-locking means such as 23 however, the stems 22 often turn somewhat about their longitudinal axes, and hence move the bells 24 out of their proper positions. To compensate for this, novel provision is made.

The outer end of each stem 22 is provided with an enlarged head 25 having a central recess 26 which opens through its outer extremity. The bell 24 rotatably surrounds the outer end portion of the stem 22 and is recessed to receive the head 25, and a set screw 27 is provided for normally holding the bell 24 against rotation upon the stem 22. This set screw is threaded outwardly through the wall of the recess 26, has its outer end in contact with the bell and has its head exposed for operation within the recess 26. In case any stem 22 and its bell 24 should turn about the longitudinal axis of the stem, the set screw 27 may be loosened, the bell 24 restored to its original position, and said screw again tightened, thereby holding the bell which was previously out of adjustment, back in its properly set position.

As usual, the mouth ring 7 and the bells 24 are disposed in proper spaced relation so that the clay extruded through the spaces between them, will constitute the sides and the dividers of the tile or conduit. The hold-back bars 12 may be adjusted as may be necessary, without the necessity of disassembling any parts of the die or the hydraulic press, and any time one or more of the bells 24 may rotate to improper position, they may be restored to their original relation and again locked. This re-adjustment may also be effected from the exterior of the die without the necessity of totally or partially disconnecting any parts.

It will be seen from the foregoing that novel provision has been made for carrying out the objects of the invention, in an advantageous manner, and attention is again invited to the fact that within the scope of the invention as claimed, variations may be made.

I claim:

1. In an extruding die, a continuous side wall, a substantially continuous hold-back projecting inwardly from said wall between the inlet and outlet ends of the latter, and means for adjusting said hold-back inwardly or outwardly to vary the amount which it projects from said side wall, said means being

accessible for operation at the outer circumference of said continuous wall.

2. In an extruding die, a continuous side wall having a continuous groove extending throughout its inner circumference and openings from said groove to the outer circumference of the wall, hold-back bars slidably received in said groove, and means connected with said hold-back bars and passing through said openings for inwardly or outwardly adjusting said bars, said means being adjustable from the exterior of the die.

3. In an extruding die, a continuous side wall having a continuous groove extending throughout its inner circumference and openings from said groove to the outer circumference of the wall, hold-back bars slidably received in said groove, and adjusting screws threaded through said openings and having swivel connections with said hold-back bars for adjusting the latter inwardly or outwardly, said screws being adjustable from the exterior of the die.

4. In an extruding die, a side wall embodying a main continuous section and a mouth ring section secured to said main section in edge-to-edge relation therewith, one of said sections having a stepped formation at its inner edge coacting with the other section in providing an internal groove, said one section being formed with openings from said groove to its outer side, hold-back bars slidably received in said groove, and adjusting screws threaded through said openings and having swivel connections with said hold-back bars for adjusting the latter inwardly or outwardly, said screws being adjustable from the exterior of the die.

5. In an extruding die, a continuous side wall, a bridge spanning the same, a stem, means securing said stem to said bridge, said stem being capable of accidental turning about its longitudinal axis, a bell rotatably mounted on the free end of said stem, and releasable means independent of said stem securing means for normally holding said bell against turning on the stem, release of said means allowing bell-turning if necessary to compensate for accidental turning of the stem, the free end of said stem being surrounded by said bell and having a recess, said releasable means consisting of a set screw threadable outwardly through the wall of said recess and abutting said bell, the head of the screw being accessible within said recess.

6. In an extruding die, a continuous side wall, a bridge spanning the same, a stem, means securing said stem to said bridge, said stem being capable of accidental turning about its longitudinal axis, a bell rotatably mounted on the free end of said stem, and releasable means independent of said stem securing means for normally holding said bell against turning on the stem, release of said means allowing bell-turning if necessary

to compensate for accidental turning of the stem, the free end of said stem having an enlarged integral head received in said bell, said head having a recess opening through its outer extremity, said releasable means consisting of a set screw threaded outwardly through the wall of said recess and abutting said bell, the head of the screw being accessible within said recess.

10 In testimony whereof I have hereunto affixed my signature.

WALTER HERBERT MAYHEW.
